BOTTLE

Andrew J. Plattner, 17214 Wyoming, Detroit, Mich.

Filed Nov. 25, 1964, Ser. No. 82,783

Term of patent 14 years

(Cl. D58—6)

FIG. 1 is a perspective view of a bottle illustrating my new design;

FIG. 2 is a bottom plan view thereof; and,

FIG. 3 is an enlarged fragmentary sectional view of the bottle illustrated in FIG. 1, taken along the line 3—3 thereof and looking in the direction of the arrows.

I claim:

The ornamental design for a bottle, substantially as shown.
